UNITED STATES PATENT OFFICE.

BERTRON G. HARLEY, OF ARKENDALE, VIRGINIA.

RUDDER.

Application filed April 14, 1923. Serial No. 632,028.

To all whom it may concern:

Be it known that I, BERTRON G. HARLEY, a citizen of the United States, residing at Arkendale, Virginia, have invented certain new and useful Improvements in Rudders, of which the following is a specification.

This invention relates to rudders and like devices for steering, or otherwise directing the movements of, a ship in its course and, in general, provides novel means for effecting better and more efficient control of the ship's movements, not only with respect to steering but as regards, also, the reversing, slowing down, and the steadyng of the ship.

The principal and particular object of the invention is to provide a combined unitary rudder-and-deflector which will operate to guide the vessel to which it is attached directionally and to control the forward and backward motion of the vessel. To that end, the invention consists in a combination unitary rudder applicable to vessels, old as well as new, by having the new rudder attached thereto without changing the existing construction of the vessel.

The invention, then, consists essentially of a usual vertically pivoted rudder which carries mounted thereon a horizontal deflecting plane or supplemental rudder, with means for pivotally moving or adjusting the supplemental rudder irrespective of the adjusted position of the vertical rudder. However, the operation of the structure gives such novel and advantageous results that I consider it is the results obtained rather than the specific means by which they are brought about. So, in interpreting the scope of my claims, and in considering what are equivalents it is to be understood that the invention contemplates any arrangement of elements which will produce the results hereinafter enumerated, so long as it embodies a rudder of the combined, unitary, type.

Among the said results referred to are: Backing the boat without reversing the propeller; moving the stern of the boat laterally; "braking" the boat to bring it to rest quickly; to prevent squatting at the stern, and to ease the boat in a sea-way.

Other objects and results of the invention will appear from the following description, read in connection with the accompanying

drawings illustrating an embodiment of the invention and in which:

Figure 1 is a view of the invention, in side elevation, as applied to the stern of a boat.

Figure 2 is a bottom view thereof.

Figure 3 is a sectional detail view, illustrating the relative arrangement of the rudder elements.

Figure 4 is a detail view, in top plan, of the rudder and tiller connection.

Figure 5 is a view in end elevation of a slightly modified deflector element, the same being curved rather than a plane and substantially concavo-convex.

Figure 6 is a sectional view on the center line of Fig. 8.

Figure 7 is a bottom view of the boat's stern, showing the rudder and deflector positioned for reverse drive.

Figure 8 is a similar view showing the parts positioned for effecting a port turn, and

Figure 9 is a similar view, showing the parts positioned for effecting a starboard turn.

In the accompanying drawing, the vessel in which my invention is incorporated is a boat, indicated generally by reference character 10, is represented as having the usual overhanging stern 11, propeller 12, and the rudder brace 13 which receives the pintle of the ordinary rudder for which the present invention is substituted. This brace, as will later be seen, is utilized in a similar capacity for the rudder of the invention.

In the invention, the rudder consists of two main parts or blades 14 and 15. Part 14 corresponds, in practice, to the ordinary and well known type of vertically pivoted rudder blade used in steering boats, and is intended to be substituted for the latter, occupying in operative position the space between the rudder brace 13 and the overhanging stern 11, as clearly shown in Figure 1. The rudder pintle 16 which engages in step bearing 17 of the rudder brace may be a part of or a separate piece secured to the blade at the lower end thereof. Secured to the blade at its upper portion is the end 18 of the rudder post, the same comprising a hollow tubular body 19 extending upwardly through the stern of the boat and having a bearing in the fixed bearing sleeve 20. Beyond the sleeve, the post has an inte-

gral lateral extension including lugs 21 between which is fulcrumed the tiller 22 which is mounted to turn on a horizontal bearing pin 23. From this arrangement it will at 5 once be seen that the shifting of the rudder laterally for steering the boat to either side is readily accomplished by movement of the tiller in the customary manner. Moreover, the tiller is capable of up and down movement when rocked on the pin 23 for a purpose presently to appear.

Part 15 of the device is substantially circular in configuration and may be either a plane, as in Figures 1 and 2, or curved as 15 shown in Figures 5 and 6. This part constitutes a supplemental rudder or deflector and is provided with a transverse central slot 24 terminating inwardly of opposite edges of the blade to provide an opening of 20 such dimensions as to adequately accommodate therein the rudder blade 14 over which the deflector is arranged as seen in Figure 3 so that both parts are disposed in right angular relation with respect to each other. 25 Integral with the deflector 15 is a transverse bearing or hub 25 extending at right angles to and on opposite sides of the slot 24 to receive the rod 26 by means of which the deflector is mounted for limited rotation 30 about a horizontal axis. The axis rod 26 is supported at a central point within the hub 27 of part 14. Deflector 15, being thus revolvably mounted, may be adjusted to any 35 inclination from the horizontal to the vertical irrespective of the adjusted position of the rudder blade 14. One or more stops 28 may, if desired, be provided on the deflector for abutment with some suitable part of the supporting structure, as will be understood from the dotted lines of Figure 1, 40 so as to limit the rotation of the deflector.

The adjustment of the deflector is effected by movement in an up-and-down direction of the tiller 22 to which it is connected by 45 means of suitable links 29 and 30; the said links being relatively pivoted at their adjacent ends and having their respective opposite ends pivoted to the tiller and to the deflector in the manner illustrated. The 50 tiller thus controls the adjustment of both parts of the rudder whether for steering or to regulate the forward, backward or any other motion of the craft.

The operation of the invention is graphically illustrated in the bottom plan views of 55 Figures 7, 8 and 9 to which reference will now be had. Attention is directed, however, to the fact that in Figures 1 and 2 the parts are in what may here be termed their neutral position. In other words, the vertical rudder blade 14 is in alignment with the plane of the boat's keel for direct steering while the deflector blade 15 is disposed within the horizontal plane of the propeller shaft 60 and offers little or no resistance to the cur-

rents set up by the propeller. Such will usually be the disposition of the parts during the forward travel of the boat. To back the boat without reversing the propeller, the tiller is shoved down hard, moving the rotatable deflector 15 in the arc of a circle until it has assumed the vertical position indicated in the dotted line structure of Figure 1. Hence, the currents set up by the propeller 70 12 will, as indicated by the arrows of Figure 7, squarely impinge the deflector and be thereby deflected back through a course indicated by the said arrows. The impulse imparted to the deflector by the force of the deflected currents is continuous as long as the propeller is revolving and being counter to the direction in which the boat is traveling will ultimately force the boat backward, thus completely reversing the direction of travel. It has been found, in 75 practice, that when the deflector is thus brought to the vertical position indicated that there is at first a gradual though rapid decrease in the forward speed of the boat until the latter is brought to a quick stop, 80 and then a backward movement at a rapidly increasing ratio of speed. Hence, in its vertical position the deflector acts as a drag for "braking" the boat, that is, checking or retarding the speed of the same especially 85 when it is desired to bring the boat quickly to rest. This is accomplished by stopping the revolution of the propeller as soon as the forward momentum of the boat has been checked by the positioning of the deflector 90 vertically as above explained.

With reference to steering it will be noted from Figures 8 and 9 that when the rudder is shifted laterally for turning the boat to either side more of the currents impinge 95 one side of the device than the other. Moreover, the greater number of currents, indicated at 31, impinge the adjacent inclined surfaces of both parts 14 and 15 from which they are deflected in a lateral direction to 100 the line of travel. The lesser number of currents, indicated at 32, impinge only the outer portion of the deflector. Hence, the force of the greater number of deflected currents serves to repel the stern in the opposite direction, the said stern, instead of the prow of the boat, being thus moved laterally in the arc of a circle when turning. The stern moves, of course, opposite to the 105 direction of the turn so that when making a 110 port turn, as in Figure 8, the propeller-generated currents are deflected from the port side of the stern, causing the latter to swing to the starboard for pointing the prow of the boat in the desired direction. In like manner, the starboard turn is effected by deflecting the currents from the starboard side of the stern. This method of steering by moving the stern, rather than the prow 115 of the boat, laterally offers certain obvious 120 125 130 advantages.

advantages in threading a passage through water traffic, in making short turns, easing the boat into a dock, and in many other ways.

- 5 By adjustment of the deflector to an inclination between the horizontal and the vertical, the currents may be readily deflected at an angle suitable for effecting a thrust counter to the sway or rock of the boat, making it possible to ease the latter in a sea-way. Hence, by the adjustment of the deflector to the appropriate angle of inclination, it is likewise possible to prevent squatting at the stern.
- 10 15 From the foregoing it is believed that the novelty and operation of the invention will be readily understood and, further, that the same comprehends all such changes and modifications thereof as come properly within the scope of the invention as hereinafter claimed.

Having thus described the invention, what I claim as new and desire to secure by Letters Patent is:

- 20 25 1. For attachment to a boat, a vertically pivoted main rudder and a horizontally pivoted supplemental rudder carried by said main rudder inoperative when in horizontal position and operative when in vertical position, said supplemental rudder having a substantially concave face presented to the boat when in vertical position.
- 30 2. The device of claim 1 in which the supplemental rudder is disc shaped.

3. In combination in a boat, a propeller, a composite rudder adapted to be acted upon by the water currents forced thereagainst by said propeller comprising a vertically pivoted plane and a horizontally pivoted plane carried by said first mentioned plane 40 inoperative when in horizontal position, and means for adjusting the second said plane to a vertical position transverse to the first said plane irrespective of the position of the first said plane.

4. In combination in a boat, a propeller, a composite rudder adapted to be acted upon by the water currents forced thereagainst by said propeller comprising vertically and horizontally pivoted planes, and means for 50 adjusting the horizontally pivoted plane to reverse the direction of motion of the boat without the reversal of said propeller.

5. The device of claim 4 in which said means include means for adjusting said 55 planes with respect to the boat and the water currents from said propeller and to each other whereby the stern of the boat may be moved laterally to either side.

6. The device of claim 4 in which said 60 means comprise means for adjusting the said planes with respect to the water currents from said propeller and to each other whereby the stern of the boat may be moved to either side with the bow of the boat 65 as a pivot.

In testimony whereof I affix my signature.
BERTRON G. HARLEY.
